L. H. BURLIN

FLOOR FASTENING FOR PEDESTALS

Filed Dec. 6, 1923.

Fig. 2.

Inventor:
Leslie H. Burlin,
by Robert Burns,
Atty.

UNITED STATES PATENT OFFICE.

LESLIE H. BURLIN, OF CHICAGO, ILLINOIS, ASSIGNOR TO CHICAGO HARDWARE FOUNDRY COMPANY, OF CHICAGO, ILLINOIS, A CORPORATION OF ILLINOIS.

FLOOR FASTENING FOR PEDESTALS.

Application filed December 6, 1923. Serial No. 678,856.

To all whom it may concern:

Be it known that I, LESLIE H. BURLIN, a citizen of the United States of America, residing at Chicago, in the county of Cook and State of Illinois, have invented a certain new and useful Improvement in Floor Fastenings for Pedestals, of which the following is a specification.

This invention relates to that class of fastening devices for securing the pedestals of stools and the like to the floors of lunch and other like rooms, and has for its object;

To provide a structural formation and combination of parts whereby a substantial attachment of a pedestal or support to a floor or the like in a ready and convenient manner is provided, capable of release in a like manner, and with which the entire mechanism is enclosed from view and out-side influences, all as will hereinafter more fully appear.

In the accompanying drawing:

Fig. 1, is a sectional perspective view illustrating the present improvement applied to the pedestal of a lunch room stool.

Fig. 2, is a sectional elevation of the same.

Like reference numerals indicate like parts in both views.

30 The pedestal 1 in the present construction is of the usual hollow or tubular form, terminating at its lower end in an expanded base portion 2, in the cavity of which the present fastening means is arranged. To 35 such end the inner wall of the base 2 carry a pair of socket lugs 3, formed with open top socket recesses 4, with the adjacent ends of the lugs arranged in separated relation to provide space for the L shaped rocker 40 head of the fastening means now to be described.

The aforesaid rocker head consists of a horizontally extending forked toe 5, and a vertically extending operating arm 6 integrally connected together and having at their point of intersection laterally extending pivot studs 7 adapted for pivotal bearing in the socket recesses 4 of the lugs 3 aforesaid, so as to provide a pivoted connection between the rocker head and the pedestal base.

The free end of the arm 6 is formed with a slot or opening for the passage of the operating screw bolt 8 of the device, and 55 preferably with stop lugs 9 adjacent to said

slots or opening for engagement with the sides of the nut 10 of the bolt 8 to prevent turning of the nut with the bolt 8 in the operation of the parts. The operating bolt 8 is arranged horizontally and passes through an orifice in the wall of the hollow pedestal 1, with its fixed operating head 11 having bearing at the outer end of said orifice.

The present device is adapted for engagement with a headed stud 12 fixed to the floor or other surface, with the head 13 thereof a sufficient distance above the floor surface to permit an entry of the forked free end of the rocker toe 3 beneath the same. By a rotation of the operating screw bolt 8 a rocking movement of rocker head is attained to either force the rock toe 3 up into substantial holding engagement beneath the head 13 of the floor stud 12, or to release such holding engagement.

The headed stud 12 will usually comprise a headed lag bolt screwed into an ordinary expansion sleeve 14 fitted in an orifice in the floor, as shown in Fig. 2.

Having thus fully described my invention, what I claim and desire to secure by Letters Patent, is:—

1. In a floor fastening for pedestals, the combination of a hollow pedestal base, a rocker member pivoted in the interior of the base, and having a horizontal toe adapted for engagement beneath a stud fixed on the surface of a floor and with an upright arm, and a horizontal screw bolt having bearing in the pedestal base and operative engagement with said upright arm.

2. In a floor fastening for pedestals, the combination of a hollow pedestal base formed with internal socket lugs arranged in separated relation, a rocker member arranged between said lugs and formed with lateral pivot studs for engagement with said lugs, said rocker member having a horizontal toe adapted for engagement beneath a stud fixed on the surface of a floor and with an upright arm, and a horizontal screw bolt having bearing in the pedestal base and operative engagement with said upright arm.

3. In a floor fastening for pedestals, the combination of a hollow pedestal base formed with internal socket lugs arranged in spaced relation, the socket recesses of the lugs having an open top form, a rocker

105

110

- member arranged between said lugs and ranged between said lugs, said rocker member formed with lateral pivot studs for engagement in said socket recesses, said rocker member having a horizontal toe adapted for engagement beneath a stud fixed on the surface of a floor with an upright arm, and a horizontal screw bolt having bearing in the pedestal base and operative engagement with said upright arm.
- 10 4. In a floor fastening for pedestals, the combination of a hollow pedestal base, a rocker member pivoted in the interior of the base and formed with a fork ended horizontal toe adapted to engage beneath the head of a stud fixed on the surface of a floor and with an upright arm, a screw bolt passing through an orifice in the pedestal base and provided at one end with a fixed operating head having bearing at the outer end of said orifice and at the other end with an adjustable nut having bearing against the aforesaid upright arm.
- 15 5. In a floor fastening for pedestals, the combination of a hollow pedestal base formed with internal socket lugs arranged in separated relation, a rocker member adapted to engage beneath the head of a stud fixed on the surface of a floor and with an upright arm, and a horizontal screw bolt having bearing in the pedestal base and operative engagement with said upright arm.
- 20 6. In a floor fastening for pedestals, the combination of a hollow pedestal base, a rocker member pivoted in the interior of the base, and having a horizontal toe adapted for engagement beneath a stud fixed on the surface of a floor and with an upright arm, a screw bolt passing through an orifice in the pedestal base and provided at one end with a fixed operating head having bearing at the outer end of said orifice and at the other end with an adjustable nut having bearing against the aforesaid upright arm.

Signed at Chicago, Illinois, this 3rd day

of December, 1923.

LESLIE H. BURLIN.
